UNITED STATES PATENT OFFICE.

WARREN McARTHUR, JR., OF CHICAGO, ILLINOIS.

TUBULAR LANTERN.

1,070,152.

Specification of Letters Patent.

Patented Aug. 12, 1913.

Application filed December 26, 1911. Serial No. 667,587.

To all whom it may concern:

Be it known that I, WARREN McARTHUR, Jr., a citizen of the United States, residing at Chicago, in the county of Cook 5 and State of Illinois, have invented a new and useful Improvement in Tubular Lanterns, of which the following is a specification.

This invention relates to that class of 10 tubular lanterns which are provided above the globe with a globe holder which is movable up and down in the top portion of the lantern and which when lowered upon the globe holds the latter in its normal position, 15 and when raised releases the globe so that it can be manipulated for giving access to the burner and for other purposes.

The object of this invention is to produce 20 a lantern of this general character in which a short globe is used, a globe which has the form, practically, of the lower large portion of an ordinary tubular lantern globe and does not contain the upper contracted portion, so that the globe holder is comparatively 25 long while the globe is short and of comparatively large diameter at the top, whereby several important advantages are secured, as will appear from the following description.

30 In the accompanying drawings: Figure 1 is an elevation of a tubular lantern of the cold blast type embodying this invention. Fig. 2 is a fragmentary side elevation of the upper part of the lantern at right angles to Fig. 1. Fig. 3 is a horizontal section on line 3—3, Fig. 1. Fig. 4 is an elevation, partly in section, showing the globe holder raised from the globe. Fig. 5 is a side elevation, partly in section, showing the globe 35 holder raised and the globe swung away from the wick tube. Fig. 6 is a front elevation, partly in section, showing the lower portion of the lantern in this position. Fig. 7 is an elevation, partly in section, of a 40 tubular lantern having a different style of globe holder.

Like reference characters refer to like parts in the several figures.

Referring to Figs. 1—6, A represents the 45 oil pot, B the tubes, C the globe, D the globe holder, and E the lantern top in which the globe holder is movable up and down. 50 10 represents the usual air chamber on the oil pot, 11 the burner arranged within this chamber, 12 the wick tube and 13 the cone. 55 14 represents the perforated plate on which

the globe rests and which is attached to the lower part of the lantern structure by a hinge 15 so that this plate, with the globe attached thereto, can be swung back when access is desired to the wick tube. The cone 13 is preferably secured to the globe plate 14, as shown, so that upon swinging the plate back the wick tube is exposed and freely accessible. 16 represents guard wires 60 which are secured to the globe plate and which hold the globe releasably on the same. Any other convenient means of so holding the globe on the plate can be employed. The globe is comparatively short 65 and large in diameter, having approximately the shape of the lower large portion of an ordinary tubular lantern globe without the upper contracted portion, so that the globe has practically the same diameter 70 at the top which it has at the bottom. The lower portion 17 of the globe holder flares 75 downwardly and is provided with bifurcated guides 18 by which it is guided on the tubes. The upper approximately straight or 80 cylindrical portion 19 of the globe holder is arranged within the inner wall of the top E, which wall is separated from the outer wall by an annular passage 20, Fig. 4, through which the air enters the tubes. The 85 up and down movement of the globe holder is best effected by a transverse lifter shaft 21, which is journaled in bearings 22, 23, on the tubes and provided at one end with a lever 24. This shaft passes transversely 90 through the globe holder which is provided on each side with a horizontal slot 25, Fig. 2, and the relation of the shaft, lever and slots is such that when the lever is turned up and the holder lowered, as represented 95 in Figs. 1 and 2, the shaft is adjacent to the forward end of the slot and beyond the dead center and holds the globe holder firmly down on the globe and the latter on the globe plate and the globe plate on the 100 air chamber, thereby holding these parts tightly against each other, while when the lever is turned down and the holder raised, 105 Figs. 4 and 5, the shaft is adjacent to the rear end of the slot and holds the globe holder in its raised position. The lantern top E is provided with suitable openings 110 26 for the escape of the products of combustion and can be drawn out of a single blank of sheet metal, if desired. Upon raising the globe holder from the globe the latter and the globe plate can be tipped back

on the hinge of the plate, whereby the wick tube and the air chamber are uncovered and rendered accessible.

The short globe employed in this lantern 5 is comparatively wide at the top, which renders the cleaning of the globe on its inner side easy, the globe does not get as hot as an ordinary contracted globe and is therefore less liable to crack or become 10 broken, and the globe is more easily packed for shipment than an ordinary globe. The globe is so short that it is possible to light the wick through the top of the globe on raising the holder, which facilitates the 15 lighting of the lantern in the wind. The lifter mechanism connected with the globe holder is easily operated because it is located in a part of the lantern which is easily reached by the thumb of the right hand 20 holding the lantern, and since the lifter is not required to lift the weight of the globe but only that of the holder, the movements of the holder are effected with little effort.

The lantern represented in Fig. 7 differs 25 from that represented in Figs. 1-6 in that in Fig. 7 the holder is forced down by a spring 27 arranged between a shoulder on the holder and the lantern top in a well known manner, while in the lantern of Figs. 1-6 30 no such spring is employed and the holder is held down simply by the lifter shaft.

I claim as my invention:

1. The combination with a tubular lantern frame having an air inlet chamber in 35 its top portion, of a globe-holding chimney which is movable up and down in said chamber and provided below said chamber with actuating slots, and a cranked lifter shaft arranged transversely on said frame below 40 said chamber and engaging in said slots for actuating said chimney, substantially as set forth.

2. The combination with a tubular lantern frame having an air inlet chamber in 45 its upper portion, of a support on which the globe rests, a globe holder which extends below said air inlet chamber and is movable toward and from the top of the globe, on which it bears, and toward and from said 50 globe support, and a lifter shaft arranged across said lantern frame below said air inlet chamber and engaging said globe holder, substantially as set forth.

3. The combination with a tubular lantern frame having an air inlet chamber in 55 its top portion, of a movable globe support, a globe resting thereon, a globe-holding chimney comprising an upper cylindrical portion which is vertically movable in said 60 air chamber and a lower downwardly flaring portion which bears upon the globe, and a cranked lifter shaft which is arranged on 65 said frame below said air chamber and

above the globe and which engages said chimney, substantially as set forth.

4. The combination with a tubular lantern frame comprising an air inlet chamber at the top, an oil pot, an air chamber upon the oil pot and a connecting tube, of a globe support which is hinged to the lower portion 70 of said lantern frame and provided with means for releasably holding the globe and with a burner cone, a globe holder which extends below said air inlet chamber and is movable toward and from the top of the 75 globe, on which it bears, and toward and from said globe support, and a lifter shaft arranged across said lantern frame below said air inlet chamber and engaging said globe holder, substantially as set forth.

5. The combination with a tubular lantern frame having an air inlet chamber in its upper portion, of a globe holder bearing upon the top of the globe and provided with substantially horizontal slots in its lower 85 portion, and a cranked lifter shaft arranged across said frame and engaging in said slots and operating to move said holder up or down by engaging the walls of said slots, substantially as set forth.

6. The combination with a tubular lantern frame having an air inlet chamber in its upper portion, of a support on which the globe rests, a globe holder which extends below said air inlet chamber and is movable 95 toward and from the top of the globe, on which it bears, and toward and from said globe support and which is provided with substantially horizontal slots, and a cranked lifter shaft which is arranged across said 100 lantern frame below said air inlet chamber and which extends through said slots in said globe holder and moves said holder up or down by engaging the walls of said slots, substantially as set forth.

7. The combination with a tubular lantern frame having an air inlet chamber in its upper portion, of a globe support, a globe holder which extends below said air inlet chamber and bears upon the top of the globe 110 and is movable toward and from the top of the globe and toward and from the globe support, and lifting mechanism arranged below said air inlet chamber and engaging said globe holder, said lifting mechanism 115 and said globe holder having means for holding the globe holder in a raised position and for holding the globe holder down upon the top of the globe, substantially as set forth.

Witness my hand in the presence of two subscribing witnesses.
